MOP

Filed March 21, 1928

FIG. 1

FIG. 2

FIG. 3

INVENTOR
J. B. HARDIE
BY J. S. Cook
ATTORNEY

UNITED STATES PATENT OFFICE

JAMES B. HARDIE, OF ST. LOUIS, MISSOURI

MOP

Application filed March 21, 1928. Serial No. 263,240.

This invention relates generally to mops, and more specifically to an improved fountain mop, the predominant object of the invention being to produce a mop which is so constructed and arranged that a body of cleansing fluid may be maintained in association with said mop at all times, from which supply of cleansing fluid portions thereof may be drawn periodically as required during the use of the mop.

In the use of mops of the type which were in general use prior to this invention, it was necessary for a person engaged in mopping a floor, for instance, to maintain a receptacle containing water or other cleansing fluid close at hand in which the mop being used might be periodically rinsed. This necessity for periodically rinsing the mop arose from the fact that it was necessary periodically to supply clean water to the mop if the mopping task was to be performed in a clean manner, since, if this were not done, part of the mopping would be done with dirty water. The task of periodically rinsing a mop was a laborious and time-consuming one, inasmuch as it generally involved continual stooping on the part of the person using the mop, with a consequential expense of energy and time.

The improved mop disclosed herein is intended to eliminate the disadvantages referred to above, and, briefly stated, comprises a chamber arranged in permanent association with the mop wherein cleansing fluid is maintained. The chamber referred to is arranged in communication with the mopping portion of the mop, so that said cleansing fluid may flow from said chamber to said mopping portion of the mop, and my improved mop also includes conveniently actuated means whereby the passage of said cleansing fluid from said chamber to said mopping portion of the mop may be controlled by the person using the mop without interrupting the mopping operation.

Fig. 1 is a view of my improved mop showing same partly in elevation and partly in section, a portion of the handle of the mop being broken away to conserve space.

Fig. 2 is an enlarged inverted plan view of

the lower portion of the handle of the mop looking toward the valve.

Fig. 3 is a fragmentary sectional view of the portion of the mop adjacent to the valve showing said valve in its open position.

In the drawing, which illustrates one embodiment merely of my invention, A designates the improved mop generally, said mop comprising a handle portion B, a head C and a mopping portion D. The mopping portion D of the mop is made of the usual cord-like material of which these portions of mops are ordinarily made, and said material is secured to the head C by means of a cord or other suitable fastening means E, which encircles a portion of the body of cord-like material and the head C in a manner to secure said cord-like material to said head (Fig. 1).

The head C is preferably cylindrical in cross-section and is provided with a bar 2 which extends transversely of said head from one side thereof to the other, said bar being relatively narrow with respect to the inside diameter of the head so that the passageway through said head is not entirely closed by said bar. The head C is also provided with annular flanges C' at its opposite ends.

The handle portion B of the mop is hollow to provide a chamber 3, said chamber having a lower wall 4 located adjacent to the lower end of the handle portion B, which wall is provided with a passageway 5, formed therethrough, which is intended for a purpose to be hereinafter set forth. At the upper end thereof the handle portion B is provided with a curved portion B', the outer end of which is closed by a suitable cap B² which may be secured to said curved portion of said handle by means of screw-threads, or otherwise if desired.

At the lower end thereof the handle portion B telescopes within the head C, as shown in Figs. 1 and 3, the outside diameter of said handle portion being such that the outer face thereof contacts closely with the inner face of the head. Extended upwardly from the bar 2 is a fixed rod 6, said fixed rod having a shoulder 6' which contacts with the top face of the bar 2 and being provided with a reduced, threaded portion 7, which passes

through an aperture formed through said bar. The reduced threaded portion 7 receives a nut 8 which contacts with the bottom face of the bar 2 whereby said rod 6 is rigidly fixed to said bar 2. Rigidly fixed to the rod 6 at the upper end thereof is a valve head 9, the lower portion of said valve head being arranged in contact with a shoulder 10 on said rod, and a portion 11 of said rod, which is of reduced diameter, being extended through an opening formed through the valve head 9.

12 designates a washer which is arranged in contact with the upper portion of the valve head 9, and 13 designates a nut which is screwed on the portion 11 of the rod 6 at the upper end thereof, said nut being forced into firm contact with said washer 12 whereby the valve head 9 is securely held on the rod 6 between the shoulder 10 and the nut 13. The rod 6 is extended through the passageway 5 as shown in Figs. 1 and 3, and when the parts of the mop are in the positions in which they are shown in Fig. 1, the lower portion of the valve head 9 contacts with the countersunk seat 5' at the upper end of said passageway 5. 14 designates an expansible coil spring, the opposite ends of which contact with the top face of the bar 2 and bottom face of the wall 4, respectively, whereby said coil spring 30 tends to force the handle portion B of the mop upwardly with respect to the head C.

In the use of my improved mop, cleansing fluid, for instance water, and a suitable soap powder, if desired, are introduced into the chamber 3 within the handle portion B, said handle portion being provided with the curved portion B' to permit of its being conveniently arranged beneath a faucet so that water may be introduced thereinto. After the cleansing fluid has been introduced into the chamber 3 as described, the cap is arranged in place to close the chamber 3 at its upper end and the mop is ready for use. Just previous to the beginning of a mopping operation with the mop, the handle portion B is pushed downwardly with respect to the head C. This action will cause the wall 4 to move out of contact with the valve head 9, as shown in Fig. 3, whereby cleansing fluid within the chamber 3 will be permitted to pass through the passageway 5 in the wall 4 and flow through the head C and saturate the cord-like material forming the mopping portion D of the mop.

55 When the proper amount of fluid has been introduced into the mopping portion D of the mop, the handle portion B is permitted to return to its elevated position in response to action of the coil spring 14, whereupon 60 the valve head 9 will again close the passageway 5 and prevent further discharge of fluid from the chamber 3 to the mopping portion D. The mopping operation may then be performed, and periodically during said mopping operation, when fresh cleansing fluid

is desired, it may be introduced into the mopping portion of the mop by merely pushing the handle portion B downwardly with respect to the head C, as already described.

I claim:

A mop comprising a mopping portion, a hollow handle providing a chamber adapted to receive cleansing fluid, a head to which said mopping portion is attached and with respect to which said handle is capable of telescoping movement, said head being located entirely outside of said hollow handle, a valve head fixedly supported by said head, and a wall providing an end wall of said chamber and having a passageway formed therethrough which may be closed by said valve head, said handle being movable to move said wall away from said valve head to permit fluid to pass from said chamber through said passageway.

In testimony that I claim the foregoing I hereunto affix my signature.

JAMES B. HARDIE.
